UNITED STATES PATENT OFFICE.

ISAAC HARTER, JR., OF DONGAN HILLS, NEW YORK, ASSIGNOR TO THE BABCOCK & WILCOX COMPANY, OF BAYONNE, NEW JERSEY, A CORPORATION OF NEW JERSEY

WATER-TUBE BOILER.

Application filed May 29, 1918, Serial No. 237,234. Renewed December 31, 1923. Serial No. 594,201.

To all whom it may concern:

Be it known that I, ISAAC HARTER, Jr., a citizen of the United States, residing at Dongan Hills, in the county of Richmond, 5 State of New York, have invented a new and useful Improvement in Water-Tube Boilers, of which the following is a full, clear, and exact description, reference being had to the accompanying drawing, forming 10 part of this specification.

My invention relates to boilers of the general Babcock & Wilcox type, wherein horizontally inclined tubes are connected to downtake and uptake headers, which, in 15 turn, are connected to a steam and water drum or drums. In certain classes of such boilers, there is a tendency for slag and other deposits to collect on the tubes, and to some extent block up the passageway for 20 the entry of the gases to the passes among and over the tubes.

My invention is designed to reduce or overcome this difficulty by a special arrangement of the lowermost rows of water tubes.

25 Referring now to the drawings, in which I show the preferred form of my invention, Figure 1 is a sectional side elevation showing one type of Babcock & Wilcox boiler, arranged in accordance with my invention; 30 Fig. 2 is a cross section of the water tubes on the line II—II of Fig. 1; Fig. 3 is an enlarged sectional side elevation of a boiler similar to that shown in Fig. 1, but showing a modification, in which the lowermost rows 35 of tubes are of smaller diameter, and Fig. 4 is a view similar to Fig. 2, but taken as a cross-section on the modification shown in Fig. 3.

In Figs. 1 and 2 of the drawings, 2 represents a bank of horizontally inclined tubes having their ends connected to lower headers 3 and upper headers 4. These headers are provided with drop-leg portions 5 and 6, into which connect two lower rows of 45 tubes 7 and 8. The downtake headers are connected to the steam and water drum 9 through tubes 10, while the upward extensions of the uptake headers are connected to the steam and water drum through horizontal water tubes 11.

I have shown a furnace chamber 12, extending substantially throughout the length of the lower tubes with double firing at both ends by underfeed stokers 13 and 14. Overlying the row of tubes 7 is a horizontal baf-

fling 15, from the inner end of which extends a vertical baffle 16. 17 is a further baffle extending through the main bank and provided with a baffle extension 18. The gases from the furnace rise through the 60 right-hand pass, flow over the superheater 19, if such is used, then descend through the middle pass between the baffles 16 and 17, and then rise through the third pass to the 65 outlet flue 20.

In the form of my invention illustrated in Figs. 1 and 2, the lowermost rows of tubes 7 and 8 are arranged so that the tubes of the row 7 are directly over the corresponding tubes of the row 8, as best shown in Fig. 2, while the tubes of the main bank 2 are staggered in successive rows, as also shown in Fig. 2. Furthermore, the tubes 7 and 8 are more widely spaced vertically than are the tubes of the main bank 2.

In the form illustrated in Figs. 3 and 4, the tubes 7^a and 8^a are of smaller diameter than the tubes of the main bank 2^a, the center-to-center spacing of the tubes across the boiler being the same in both cases, which results in the flow area through each of the rows of tubes 7^a and 8^a being greater per unit of length of pass measured along or longitudinally of the tubes than in the main bank 2^a. The tubes 7^a and 8^a are also more 85 widely spaced vertically than are the tubes in the main bank 2^a.

In this type of boiler, when used with a firing apparatus, such as an underfeed stoker, which causes slag particles to rise with the gases, slag is liable to be deposited on the lower boiler tubes and gradually close up the flow passages.

The arrangements illustrated will minimize the deposition of slag on the tubes and, moreover, will minimize the harmful effects of such deposition. By increasing the distance from the wall of a tube in the lowermost row to the nearest wall of a tube in the next row, a molten slag particle has a longer time to cool after passing the tubes in the first row before striking the wall of a tube in the next higher row, which time is further increased by increasing the flow area and correspondingly decreasing the velocity of the gases, as, for instance, is illustrated in the form shown in Fig. 4. By cooling the particles, their tendency to stick to the tubes is decreased. Moreover, if slag does accumulate on the row above the lowermost 105

row, the greater distance between the walls of the tubes in that row and the lowermost row permits a greater accumulation before the gas passages will be obstructed and, therefore, a longer time before the exteriors of the tubes must be cleaned.

The advantages of my invention will be obvious to those skilled in the art, since the tendency to clog up the free entrance of the gas in the lower part of the first vertical pass is reduced or avoided, and better efficiency is obtained. The number of the lower rows of tubes which are specially arranged to prevent slagging may be varied, the firing means may be of any suitable type, the superheater may or may not be used, and many other changes may be made without departing from my invention.

What I claim and desire to secure by Letters Patent of the United States is:—

1. The combination with a water-tube boiler having a main bank of horizontally extending inclined water tubes connecting water compartments at the front and rear, the rows of water tubes in said bank being staggered relatively to each other, of a plurality of rows of water tubes below said bank and exposed to the radiant heat of the furnace for the major portion of their length, the tubes in the lowermost row being placed under the corresponding tubes of the next row above them, a roof baffle extending longitudinally of the water tubes above the lower water tubes and having at its inner end portion an upwardly extending baffle arranged to give the gases an upward transverse pass across the water tubes of the main bank, the spacing, diameters and arrangement of the tubes being such as to give less resistance to the flow of the gases per unit of length of pass along the tubes in passing from the furnace to above the lowermost lines of tubes than the resistance to the flow of the gases in the first upward pass among the tubes of the main bank, whereby slagging of the lower water tubes is reduced, and a furnace below the lower superposed water tubes having firing apparatus of the type which causes slag particles to rise with the gases entering the water tubes.

2. The combination with a water-tube boiler having a main bank of horizontally extending inclined water tubes connecting water compartments at the front and rear, the rows of water tubes in said bank being staggered relatively to each other, of a plurality of rows of water tubes below said bank and exposed to the radiant heat of the furnace for the major portion of their length, the tubes in the lowermost row being placed under the corresponding tubes of the next row above them, a roof baffle extending longitudinally of the water tubes above the lower water tubes and having at its inner end portion an upwardly extending

baffle arranged to give the gases an upward transverse pass across the water tubes of the main bank, the spacing, diameters and arrangement of the tubes being such as to give less resistance to the flow of the gases per unit of length of pass along the tubes in passing from the furnace to above the lowermost lines of tubes than the resistance to the flow of the gases in the first upward pass among the tubes of the main bank, whereby slagging of the lower water tubes is reduced, and a furnace below the lower superposed water tubes having double-firing mechanism comprising underfeed stokers projecting inwardly from the opposite front and rear ends of the furnace.

3. The combination with a water-tube boiler having a main bank of horizontally extending inclined water tubes connecting water compartments at the front and rear, the rows of water tubes in said bank being staggered relatively to each other, of a plurality of rows of water tubes below said bank and exposed to the radiant heat of the furnace for the major portion of their length, the tubes in the lowermost row being placed under the corresponding tubes of the next row above them, a roof baffle extending longitudinally of the water tubes above the lower water tubes and having at its inner end portion an upwardly extending baffle arranged to give the gases an upward transverse pass across the water tubes of the main bank, the spacing, diameters and arrangement of the tubes being such as to give less resistance to the flow of the gases per unit of length of pass along the tubes in passing from the furnace to above the lowermost lines of tubes than the resistance to the flow of the gases in the first upward pass among the tubes of the main bank, whereby slagging of the lower water tubes is reduced, and a furnace extending underneath the lower superposed tubes for substantially their length and having mechanical stokers projecting inwardly toward each other from the opposite ends of the furnace.

4. The combination with a water tube boiler having a main bank of horizontally extending inclined water tubes connecting water compartments at the front and rear, the rows of water tubes in said bank being staggered relatively to each other, of a plurality of rows of water tubes below said bank, baffling to give transverse passes for the gases across the tubes, the distance between the wall of a tube of the lowermost row and the wall of the nearest tube in the next higher row being greater than the distance between the wall of a tube in the main bank and the wall of any tube in the next higher row of the main bank, and a furnace having firing apparatus of the type which causes slag particles to rise with the gases entering the water tubes.

5. The combination with a water tube boiler having a main bank of horizontally extending inclined water tubes connecting water compartments at the front and rear, the rows of water tubes in said bank being staggered relatively to each other, of a plurality of rows of water tubes below said bank, baffling to give transverse passes for the gases across the tubes, the distance between the wall of a tube of the lowermost row and the wall of the nearest tube in the next higher row being greater than the distance between the wall of a tube in the main bank and the wall of any tube in the next higher row of the main bank, and the spacing, diameters and arrangement of said lower rows of tubes being such as to give less resistance to the flow of the gases per unit of length of pass along the tubes in passing from the furnace to above the lowermost rows of tubes than the resistance to flow of gases in the first upward pass among the tubes of the main bank, whereby slagging of the lower water tubes is reduced, and a furnace having firing apparatus of the type which causes slag particles to rise with the gases entering the water tubes. 40
6. The combination with a water tube boiler having a main bank of horizontally extending inclined water tubes connecting water compartments at the front and rear, the rows of water tubes in said bank being staggered relatively to each other, of a plurality of rows of water tubes below said bank, baffling to give transverse passes for the gases across the tubes, the horizontal distance between walls of adjacent tubes in the lowermost row being greater than the horizontal distance between walls of tubes in the rows in the main bank, whereby a greater gas flow area per unit length of pass along the tubes and a corresponding decrease in velocity of the gases is provided through said lowermost row than through the rows of the main bank, whereby slagging of the lower water tubes is reduced, and a furnace having firing apparatus of the type which causes slag particles to rise with the gases entering the water tubes. 50
7. The combination with a water tube boiler having a main bank of horizontally extending inclined water tubes connecting water compartments at the front and rear, the rows of water tubes in said bank being staggered relatively to each other, of a plurality of rows of water tubes below said bank, the outside diameters of said tubes being different from the outside diameters of the tubes in the main bank baffling to give transverse passes for the gases across the tubes, the spacing, diameters and arrangement of the lower tubes being such as to give less resistance to the flow of the gases per unit length of pass along the tubes in passing from the furnace to above the lowermost rows of tubes than the resistance to flow of the gases in the first upward pass among the tubes of the main bank, whereby slagging of the lower water tubes is reduced, and a furnace having firing apparatus of the type which causes slag particles to rise with the gases entering the water tubes. 60
- In testimony whereof I have hereunto signed my name. 65

ISAAC HARTER, JR.
